(57) **CLAIM**

The ornamental design for an electric cooker lid, as shown and described.

DESCRIPTION

1. Electric cooker lid

1.1 : Front

1.2 : Back

1.3 : Left

1.4 : Right

1.5 : Top

1.6 : Bottom

1.7 : Perspective

1.8 : Reference view of state of use

The broken lines depict portions of the electric cooker lid that form no part of the claimed design. The dash-dot-dash broken lines in Reproduction 1.6 depict the boundaries of

(Continued)

the claimed design and form no part thereof. In Reproduction 1.8, the broken lines depict environmental subject matter that forms no part of the claimed design.

1 Claim, 8 Drawing Sheets
